UNITED STATES PATENT OFFICE.

ALBERT W. BAYLIS, OF BAY SHORE, NEW YORK.

DESIGN FOR A BEDSPREAD.

Application filed March 23, 1923. Serial No. 5,565. Term of patent 7 years.

To all whom it may concern:

Be it known that I, ALBERT W. BAYLIS, a citizen of the United States, residing at 44 Montgomery Avenue, Bay Shore, Long Island, in Suffolk County, the State of New York, have invented a new, original, and ornamental Design for a Bedspread, of which the following is a specification, reference being had to the accompanying drawing, forming part thereof.

In the drawing:

The figure is a plan view of a section of the bedspread.

I claim:

The ornamental design for a bedspread, as shown.

ALBERT W. BAYLIS.
